UNITED STATES PATENT OFFICE

2,520,998

REINFORCING MEANS FOR BOTTLE
CONTAINING CRATES

William J. Cell, Forest Hills, N. Y.

Application May 20, 1947, Serial No. 749,287

2 Claims. (Cl. 217—19)

1

This invention relates to reinforcing means for bottle-containing crates and has for one of its objects the provision of means by which the crossed-wire separators employed in crates of this character, are strongly reinforced and materially stiffened at their points of crossing and are thus held against distortion or bending under rough handling.

The crates to which the present invention is applied are customarily employed for holding square type milk bottles, and such crates usually consist of a wooden frame provided on the inside with a plurality of wire rods which extend across the crate and are secured at their ends in the frame. These rods cross one another and thus divide the crate into a number of compartments, each of which receives a bottle, the crossed rods acting as separators or partitioning elements. It has been found that unless the wires or rods are strengthened or reinforced, and particularly at the point where one wire extends at right angles across another, the wires or rods soon become bent or distorted, thus permitting rattling of one bottle against another and very often causing bottle breakage.

The present invention therefore contemplates the provision of a reinforcing element located at the junction of two wire or rod separators, which element securely holds the crossed rods, thus adding stiffness and rigidity to the same, at the same time providing positioning means by which bottles placed in the compartments defined by the wires or rods, are held from undue shifting movement, rattling and possible breakage.

These and other objects are attained by the invention, a more particular description of which will be hereinafter set forth and pointed out in the claims appended hereto.

In the accompanying drawing, wherein an illustrative embodiment of the invention is disclosed, Fig. 1 is a top plan view of portions of two wire rod separators engaged by the improved reinforcing member, with portions of the crate to which the separators are attached, being shown in section; Fig. 2 is a sectional view taken on the line 2—2 of Fig. 1, looking in the direction of the arrows; Fig. 3 is a view of the reinforcing member, looking at the underside of the same; Fig. 4 is a top plan view of the reinforcing member, and Fig. 5 is a sectional view taken on the line 5—5 of Fig. 4, looking in the direction of the arrows.

Crates of the character to which the present invention is applied are usually used for containing so-called "square" milk bottles, although

the same may, of course, be used for other purposes. Such crates generally consist of a wooden frame of rectangular shape, and the interior of the frame is divided into a plurality of bottle-receiving compartments by means of wire rod separators which criss-cross one another and have headed ends anchored in the wooden frame of the crate. The present invention contemplates means by which the wires or rods are connected together at their points of crossing; are strongly reinforced at those points, and means are provided by which the bottles located between the separators are held from undue rattling and possible breakage.

15 In the drawing, one of the sides of the frame of the crate is indicated at 1, and an end member of the frame is shown at 2. One of the wire or rod separators which extends across the frame is shown at 3 and another wire or rod separator 4 is shown crossing the rod 3 at right angles. The rods are provided with heads 5 anchored in the walls of the crate and by means of which the rods are held against longitudinal shifting movement. Crates of the character described are of 20 substantial depth and are accordingly provided with several tiers of wire rod separators, a lower tier of the separators being indicated at 6 and 7 in Fig. 2. To link together the several tiers of these separators, connectors in the form of tie 25 members or links 8 are employed. Each of these tie members includes a lower loop 9 which extends around the junction or crossing of the two lower rods 6 and 7, and an upper loop 10 which similarly extends around the crossing or junction of the 30 two upper rods 3 and 4.

35 The reinforcing member for the crossing or junction of the two upper rods 3 and 4, is shown at 11, the same consisting of a plate or disk of sheet metal distorted by suitable dies into the 40 form shown. Said reinforcing member includes a central, cylindrical dome portion or hub 12, which, when the reinforcing member is fitted in position over the junction of two rods, encloses and conceals the upper loop 10 of the link 8, and 45 also covers and conceals the crossing point of the two rods 3 and 4. Extending radially from the dome portion 12 is a pair of diametrically opposite channels 14 and 15 which are shaped to fit over the uppermost rod 3. These channels 50 thus cooperate to form a passage in which said rod 3 lies, the rod being maintained therein by means of the straps 16 which are stamped out of the material of the channels 14 and 15 and distorted downwardly to thereby underlie the 55 rod 3.

The reinforcing member also includes a skirt portion 13 which is shaped or distorted to provide a pair of diametrically opposite channels 17 and 18, these two channels being located at right angles to those shown at 14 and 15 and being also located below or at a lower level than the channels 14 and 15. The two channels 17 and 18 cooperate to form a passage for the lower rod 4, as clearly seen in Figs. 1 and 2. The skirt portion 13, in the areas located between the several channels 14, 15, 17 is provided with curved edge portions indicated at 19, such portions conforming substantially in curvature to surface portions of the bottles placed in the crate between the wire separators. The result of this arrangement is that the curved edges 19, contacting with the bottles, hold the same from undue rattling as well as protect the same from breakage during handling of the bottle-filled crates.

The reinforcing members 11 are easily fitted in position by sliding the same in place on the rods and they strongly reinforce the rods at the crossings, adding rigidity and strength to the structure as well as immeasurably protecting the bottles.

Having described one embodiment of the invention, it is obvious that the same is not to be restricted thereto, but is broad enough to cover all structures coming within the scope of the annexed claims.

What I claim is:

1. In a reinforcement of the character described, a pair of crossed rods, a vertical rod connector having a single loop fitted about the junction of the two crossed rods and enclosing the two rods, a reinforcing plate having a central dome enclosing the junction of the crossed rods and enclosing and concealing the loop fitted about the same, an upper pair of channels extending ra-

10 dially from the dome and through which the uppermost of the crossed rods passes, a lower pair of channels extending from the dome and through which the lowermost of the crossed rods extends, the several channels being connected by downwardly-extending curved-edge webs conforming in curvature to the shape of bottles placed between the rods, and the upper pair of channels having straps extending below the rod passing through such channels.

2. In a reinforcement of the character described, a pair of rods crossing one another, a vertical connector in the form of a rod having a single loop at its upper end, said loop extending around the junction of the two rods and enclosing both of said rods within its loop, a plate fitted over and covering the junction of the two rods and fitting over the loop, said plate having a centrally-located raised and domed part fitting over and covering and enclosing the loop, said plate having distorted parts shaped to form an upper channel and a lower channel through which the crossed rods respectively extend, said plate also having arcuately curved web portions located between the channels, said web portions conforming substantially to the curvature of bottles placed between the rods.
